UNITED STATES PATENT OFFICE.

WILLIAM F. HOCHSPEIER AND LOUIS P. HOCHSPEIER, OF UNION HILL, NEW JERSEY.

SWIFT FOR SILK-WINDING.

SPECIFICATION forming part of Letters Patent No. 417,424, dated December 17, 1889.

Application filed August 20, 1889. Serial No. 321,363. (No model.)

To all whom it may concern:

Be it known that we, WILLIAM F. HOCHSPEIER and LOUIS P. HOCHSPEIER, of Union Hill, in the county of Hudson and State of New Jersey, have invented a new and Improved Swift for Silk-Winding, of which the following is a full, clear, and exact description.

This invention relates to swifts for silk-winding, and has for its object to provide a swift by means of which the skein thereon will be kept spread out and held in a steady position, can be readily and quickly loosened thereon, and can be beaten on the swift to spread the silk and prevent it from catching.

The invention consists of a swift constructed as hereinafter described and claimed.

Reference is to be had to the accompanying drawings, forming a part of this specification, in which similar figures of reference indicate corresponding parts in all the views.

Figure 1 is a side view of a swift constructed in accordance with this invention. Fig. 2 is an end view of the swift, partly in vertical section; and Fig. 3 is a detail view, partly in section, on the line xx , Fig. 2.

Heretofore in the swifts employed in silk-winding wires or cords have been employed with the rigid arms of the swift, over which cords the skein extended. The cords were shifted on the arms of the swift to adjust the skein by slipping them along on the arms. The use of cords in this way on the arms of the swift has been found to be objectionable, owing to their not keeping the skein properly in position and on account of their not being readily shifted to adjust the skein. These objections have been overcome by means of this invention, in which wooden bars are employed in place of wires, the wooden bars having an elastic support, so as always to be held outward against the skein and give a steady tension thereto.

In the construction of this invention, 1 indicates the hub of the swift, provided with hollow radial arms 2. The hub is bored radially, and the arms 2 are seated at their inner ends in the sockets thus formed. Within the central transverse bore of the hub its spindle 93 is rigidly secured, the

trunnions or bearings of the spindle being formed by the pointed ends of the spindle. Within the arms are located radially-movable rods or bars 3, limited in their outward movement by means of a pin 4 in each rod 3 engaging a slot 5 in each arm 2. The bars 3 and sockets in arms 2 are preferably square to give a steady bearing to the bars 3, as shown in Fig. 3. The inner ends of the bars 3 rest against a coiled spring 6, located in the hollow arms 2, and by their tension serving to hold the bars 3 in extended position.

Upon the outer end of each of the bars 3 is mounted a cross-bar 7, over which a skein of silk is placed, the skein being held from slipping off laterally therefrom by means of pins 8 at the ends of bars 7. The pins 8 correspond to the ends of the parallel radial arms extending from the hub in the old form of swift, and the cross-bars 7 correspond to the cords extending crosswise and connected to each pair of parallel radial arms and over which the skein extends.

The skein of silk on the swift in this invention extends over the bars 7, and is held steadily thereon by the tension of the springs 6 holding the bars 7 outward against the skein. The silk is permitted to spread out on the bars 7 and cannot get loose, as the bars 7 are held steadily against the skein by the springs 6, with a steady tension always maintained in the skein.

All of the foregoing parts are formed of wood to secure lightness, except the springs, the stops 4, and the central spindle-rod, which are of metal. The object of thus forming the swift is to render it just as light as possible, so it may be rotated without breaking the finest or weakest strand of silk.

The skein can be beaten on the swift by placing the hand inside of the skein and beating it a little, which makes the ends straight and spreads the skein out, thus making it less apt to catch again.

When an end of the skein gets caught or tangled, it can be loosened in less time than it can on the old form of swift by giving the skein a snap with the fingers, which causes the springs to give and at once loosens the end.

By means of this invention, also, the skein is more easily adjusted on the swift than with the old form. Curved cross-bars have also been used; but no pins 8 were provided, and hence the skein can be beaten without removing it from the swift or reel; but with such curved cross-bars the tendency is to crowd the silk to the center, making it liable to tangle, and if the skein were beaten it would fall off.

Having thus described our invention, what we claim as new, and desire to secure by Letters Patent, is—

The herein-described swift, comprising a

hub, radial hollow slotted arms projecting from the hub and immovable toward or from each other, the bars 3, sliding in said arms and provided at their outer ends with cross-bars 7 and pins 8, the stops 4, passing through the slots into the bars, the springs 6, and the hub bearings or trunnions rigidly secured to and projecting from opposite sides of the hub, substantially as set forth.

WILLIAM F. HOCHSPEIER.

LOUIS P. HOCHSPEIER.
